(No Model.)

W. EDENBORN.
MACHINE FOR COILING WIRE.

No. 429,511.

Patented June 3, 1890.

UNITED STATES PATENT OFFICE.

WILLIAM EDENBORN, OF ST. LOUIS, MISSOURI.

MACHINE FOR COILING WIRE.

SPECIFICATION forming part of Letters Patent No. 429,511, dated June 3, 1890.

Application filed October 9, 1889. Serial No. 326,426. (No model.)

To all whom it may concern:

Be it known that I, WILLIAM EDENBORN, of the city of St. Louis, in the State of Missouri, have invented a certain new and useful Improvement in Machines for Coiling Wire, of which the following is a full, clear, and exact description, reference being had to the accompanying drawings, forming part of this specification.

10 My invention relates to an improved device for coiling wire as it comes from the finishing-rolls of a reducing-mill; and my invention consists in features of novelty hereinafter fully described, and pointed out in the claims.

15 Figure I is a side elevation illustrative of my invention. Fig. II is a section taken on line II II, Fig. I. Fig. III is a detail top view. Fig. IV is an enlarged detail section of the 20 outer end of the distributing-tube. Fig. V is a similar view of the inner part of the distributing-tube.

25 Referring to the drawings, 1 represents a pair of rolls, through which the wire passes just before being coiled. From the rolls the wire passes through a pipe or tube 2 3. This tube 2 3 is made in two sections, one telescoping the other, as shown in Fig. V. The 30 part 2 of the tube is rigidly secured to an arm 4 of a supporting-standard 5, and the part 3 of the tube is supported by a ball-and-socket connection with the standard 5, as shown in Fig. I. It will thus be seen that the outer part 3 of the tube is free to move laterally and vertically while it is held from longitudinal movement.

35 6 represents a rod or pitman secured to the outer end of the part 3 of the tube, preferably by means of a ball-and-socket joint, as 40 shown at 7 in Fig. I. This pitman or rod is fulcrumed to a hanger 8 at 9 by means of a box 10, having preferably a ball-and-socket connection with the rod or pitman. The upper end of the rod or pitman is connected by 45 a ring and eccentric 11 to an operating-shaft 12, provided with a suitable driving-pulley. It will thus be seen that when the shaft 12 is turned a circular movement will be imparted to the outer end of the part 3 of the tube, 50 the bearing between the pitman or rod and the box 10 permitting this movement; and

for the purpose of regulating the amount of movement imparted to the outer end of the tube 3, I make the box 10 vertically adjustable by means of a slot-and-pin connection 55 13 with the hanger 8. By moving the box up or down, the throw of the lower end of the pitman will be increased or diminished.

The extreme outer end or nozzle of the part 3 of the tube is preferably provided with a 60 removable bearing-nipple 15, which can be removed and replaced by another when it becomes worn. Beneath the outer end of the tube is a cylindrical body 16, which is preferably made of cone shape at its upper end, 65 and around this cylinder the wire is wound as it issues from the pipes or tubes 2 3, into which it passes from the rollers 1, the outer end of the tube describing a circle, as stated, which effects the distribution of the wire 70 around the cylinder. Surrounding the cylinder is a plate 17, secured to a rod 18, supported in boxes 19, and provided with an operating-lever 20, and preferably with a counterbalance-weight 21. When the necessary 75 amount of wire has been coiled upon the cylinder, the plate or apron 17 may be raised (by operating the lever 20) from the position shown in full lines, Fig. I, to the position shown in dotted lines, so that the coil can be 80 conveniently removed or taken away; and it may be thus removed or taken away by means of an endless belt or chain 22, provided with teeth, if necessary, and mounted on operating-rollers. 85

A coiling-machine thus constructed is cheap and durable, and effectually performs the function for which it is intended.

I claim as my invention—

1. In a wire-coiling machine, the combination of a horizontal distributing-tube, a pivoted rod or pitman suspended above the same, connected at one end to the tube and at the other end an operating-shaft, and a body around which the wire is coiled, substantially 90 as set forth.

2. In a wire-coiling machine, the combination of a horizontal distributing-tube, a body around which the wire is coiled, a rod or pitman suspended above the tube, having a ball-and-socket connection with the outer end of the tube, and a pivotal ball-and-socket con- 100

nection with a hanger, and an operating-shaft, substantially as and for the purpose set forth.

3. In a wire-coiling machine, the combination of a distributing-tube, mechanism for operating the tube, a body around which the wire is coiled as it issues from the tube, and a pivoted plate or apron provided with an op-

erating-lever for lifting the coils from the body, substantially as set forth.

WM. EDENBORN.

In presence of—

E. S. KNIGHT,

BENJN. A. KNIGHT.
